UNITED STATES PATENT OFFICE

154,541

DESIGN FOR A SHOE

William G. Heiber and William J. Heiber,
Brighton, N. Y.

Application February 12, 1949, Serial No. 822

Term of patent 7 years

(Cl. D7—7)

To all whom it may concern:

Be it known that we, William G. Heiber and William J. Heiber, both citizens of the United States of America, and both residing at Brighton, in the county of Monroe and State of New York, have invented a new, original, and ornamental Design for a Shoe, of which the following is a specification, reference being had to the accompanying drawings, forming a part thereof.

In the drawings:

Fig. 1 is a plan view of a shoe, showing our new design;

Fig. 2 is a side elevation;

Fig. 3 is a side elevation looking in the opposite direction to Fig. 2, and

Fig. 4 is a view in elevation looking from front to rear.

We claim:

The ornamental design for a shoe, as shown.

WILLIAM G. HEIBER.
